(57) **CLAIM**

The ornamental design for a microphone as shown and described.

DESCRIPTION

FIG. 1 is a perspective view of a microphone showing our new design;

FIG. 2 is a rear perspective view thereof;

FIG. 3 is a bottom perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a right-side elevation view thereof; and,

FIG. 9 is a left-side elevation view thereof.

The broken lines shown in the figures show unclaimed seams of the microphone and form no part of the claimed design

1 Claim, 9 Drawing Sheets---
